UNITED STATES PATENT OFFICE.

GEORGE POWLEY, OF TORONTO, ONTARIO, CANADA.

BLACK-LEAF CHECK-BOOK.

SPECIFICATION forming part of Letters Patent No. 310,311, dated January 6, 1885.

Application filed October 26, 1883. (Model.) Patented in Canada June 21, 1883, No. 17,032.

To all whom it may concern:

Be it known that I, GEORGE POWLEY, of the city of Toronto, in the county of York, in the Province of Ontario, Canada, commercial traveler, have invented certain new and useful Improvements in Black-Leaf Check-Books, of which the following is a specification.

The object of the invention is to devise a black-leaf check-book easily detached from its cover, and yet when in position is held securely in place; also, to devise a double-jointed back for connecting the two halves together in such a manner that when the memorandum-leaves are fastened to the back the portion of the back to which they are attached will lie flat with the half of the cover on which the leaves rest, while the other portion of the back folds over the ends of the leaves and permits the remaining half of the cover to lie flat on the leaves; and the invention consists in the peculiar combination and the construction and arrangements of parts, as hereinafter more fully described, and pointed out in the claims.

Figure 1 is a plan view of a cover without the memorandum-book, showing the double-jointed back and the pin for holding the book in position. Fig. 2 is a side view of the same. Fig. 3 is a perspective view of the pad of memorandum-leaves, showing the holes in its stub to fit over the pins in the back of the cover.

The cover is composed of a long part, A', a short part, A, and an intermediate short part, D, the parts A and D, together with the short joint between the two, being of the same length as the half of the cover marked A'. The advantages of this construction will be hereinafter pointed out.

A' is one half of the cover, having the keepers B fixed upon its inside. These keepers consist each of a strip of material pasted or otherwise fastened to the inside of the cover A', with their open edges facing each other, so that the tally-sheets C may be slipped in position. There is nothing peculiar in this kind of sheet, except that each book is supplied with two or more of them, and, being kept in the keepers B, they can easily be removed when filled up and replaced by a blank

one. It will be noticed that the back connecting the two halves of the cover has what might be termed a "double joint"—that is to say, the portion of the back marked D, upon which the pins E are fastened, has a joint, *a*, between it and the half of the cover marked A, while the portion of the cover marked A' has a larger joint, *b*, between it and the part marked D. It will thus be seen that while the portion of the cover marked A' can be opened independently, the memorandum-leaves F, which are secured to the portion of the back marked D by the pins E, lie flat with the half of the cover marked A on which the leaves rest. When the cover A' is folded down, the part *b* folds over the end of the memorandum-leaves and permits the half of the cover marked A' to lie flat on the upper part of the leaves F. It will thus be seen that the cover marked A' can be folded entirely back without interfering with the connection formed between the back D and the memorandum-leaves. It will also be noticed that by use of the short joint between the parts D and A the book may be used either side up, which has been found a great convenience in books of this class, as it very often happens that the person using the book has occasion to make some memorandum—such as, for instance, the address of the party purchasing a lot of goods, or the time the goods are to be delivered—for which purpose sheets are most always kept in the back of the book, and when he has occasion to use one of these sheets all that it is necessary to do is to turn the book over so that the part A' will lie flat on the counter or table, when the part A can be folded entirely back independently and without interfering with the connection formed between the part D and the memorandum-leaves. This cannot be done with covers formed of but two parts, said parts being connected by a long joint, as has been proposed.

G is an elastic band connected at either end to the back D, and passing over the stub ends of the memorandum-leaves. This elastic band holds the memorandum-leaves in position, while the pins E prevent the book from shifting. The elastic band is also for holding the black leaf in position, which black leaf is not

bound in with the book, but, being simply held by the elastic band, may be replaced by a new one when the old one is worn out.

What I claim as my invention is—

- 5 1. A cover for memorandum-leaves, consisting of the short part A, long part A', and the intermediate short part, D, with a joint, *a*, between said parts A and D, and a larger joint, *b*, between the parts A' and D, forming the back of the book and connecting the parts A' and D, substantially as and for the purpose specified.
- 10 2. A cover for memorandum-leaves, consist-

ing of the short part A, long part A', and intermediate short part, D, with a joint, *a*, between said parts A and D, and a larger joint, *b*, between the parts A' and D, connecting said parts A' and D, and forming a protector for the ends of the leaves, said part D provided with pins E, for holding the memorandum-leaves, substantially as described.

Toronto, October 3, 1883.

G. POWLEY.

In presence of—

CHAS. C. BALDWIN,
LEWIS TOMLINSON.
